W. J. BUTLER

CIGAR LIGHTER

Filed July 2, 1927

UNITED STATES PATENT OFFICE.

WILLIAM J. BUTLER, OF CRANSTON, RHODE ISLAND, ASSIGNOR TO HENRY LEDERER & BRO., INC., OF PROVIDENCE, RHODE ISLAND, A CORPORATION OF RHODE ISLAND.

CIGAR LIGHTER.

Application filed July 2, 1927. Serial No. 203,227.

This invention relates to an ignition device of the pyrophoric type having a manually operated friction wheel; and has for its object to prevent the thumb from coming in contact with the friction wheel and yet so mount the wheel that it may be readily removed and replaced when worn.

A further object of the invention is to more securely support the pivoting trunnion of the friction wheel by thickening the top wall of the fuel reservoir at the point of mounting the trunnion to give an increased bearing support therefor.

With these and other objects in view, the invention consists of certain novel features of construction, as will be more fully described, and particularly pointed out in the appended claims.

In the accompanying drawings:

20 Figure 1 is a side elevation of the ignition device.

Figure 2 is a top plan view thereof.

Figure 3 is a sectional view through the ignition means which is mounted on the top 25 of a fuel reservoir.

Figure 4 is a side elevation of the wheel unit providing both a friction wheel, and a separate or spaced thumb wheel.

Figure 5 is a side elevation of the washer 30 or support for the wheel unit.

Figure 6 is a side elevation of the trunnion.

Figure 7 is a sectional view through the wick tube with a fragment of the casing 35 and its closing cap shown in section.

Figure 8 is a sectional view taken at right angles to that shown in Figures 3 and 7 through the wick tube and the trunnion mounting for the friction wheel of the ignition means mounted on the top of the fuel 40 reservoir.

Fig. 9 is a fragmental perspective view of the top part of the lighter.

It is found in practice desirable to provide an ignition device of a size to be carried about in the pocket of the user, which will be simple and positive in its operation, inexpensive to manufacture and yet one wherein the ignition parts are mounted on 45 the top of a fuel reservoir with the abrasive wheel protected against accidental contact and with the parts most subjected to constant wear removably mounted so that they can be easily and quickly replaced; and in 50 order to provide a device having such char-

acteristics, I have mounted a friction wheel and thumb wheel unit on a removable trunnion, the unit being supported by means of a separate washer encircling the trunnion and permitting the unit to be removed by 60 removing the trunnion and washer and dropping the unit from beneath the protecting guard or band encircling the friction element, whereby the same may be easily replaced or interchanged at will; and 65 the following is a detailed description of the present embodiment of this invention and showing one means by which these advantageous results may be accomplished:

With reference to the drawings, 10 designates the fuel reservoir or casing which has a top wall 11 and a bottom wall 12 through which latter wall the reservoir may be filled by removal of the cap 13 which has threaded engagement with the bottom 75 wall, as clearly illustrated in Figure 3. An absorbent material 14, such as cotton or the like, is placed in the fuel reservoir when desired for taking up the volatile fuel.

A short tube 15 extends from the fuel 80 reservoir 10 in which a wick 16 fits snugly which tube may be closed by a cap 17 hingedly supported on a pin 18 in the standard 19, as desired. A plunger 20 is pressed into contact with one of the flat sides 21, 22 or 85 23 of the end of the arm 24 by means of a spring 25 and serves to hold the cover for the wick in the desired open or closed position.

In order to ignite this wick, I have provided a standard 26 which supports the tube 27 in which pyrophoric material 28 is slideable and pressed by means of a spring 29 and thumb screw 30 against the friction wheel 31 mounted on the trunnion 32 as will 90 be clearly apparent in the sectional showing of Figure 3. The friction wheel 31 is integral with a sleeve unit which also has integrally formed thereon a thumb wheel 40 of a size considerably larger than that of the friction wheel but which is not formed with a cutting edge to injure the thumb.

A guard 33 formed integral with the pyrophoric tube 29 is in band shape and extends about or encircles the friction wheel 31 to 95 guard the same against accidental contact with the thumb. The opening through band 33 is of a size to leave clearance between it and the friction wheel and also is of such a size as not to contact with the slotted head 100 110

34 of the trunnion 32 but permit it to pass freely through this band opening in removal of the trunnion from the reservoir.

The trunnion 32 has a threaded portion 35 which engages a threaded recess 36 in the top wall 11 of the fuel casing. The stock 37 is thickened about this recess 36 to give an increased depth or bearing and permit a greater or more extended threaded engagement of the stud with the top of the casing. It will be observed that the trunnion or stud 32 has a support only at one end.

A washer 38 is positioned about the trunnion 32 and between the thumb wheel 40 and the top wall 11 of the casing to support the friction wheel in its desired position opposite the end of the pyrophoric tube. In removing the friction wheel after the same has become worn, it is merely necessary to insert 20 a screwdriver in the slotted head of the trunnion 32 and back the screw-threaded part 35 thereof out of its recess in the top 11 and lift the trunnion 32 outwardly through the band-shaped guard 33 and then remove 25 the washer 38 from beneath the wheels to permit the abrasive part to drop from beneath the guard 33 and the unit to be removed to be repaired or replaced by another wheel unit.

30 I have provided a very simple and economical construction of lighter and have so mounted the moving parts that they may be quickly and easily replaced when desired and yet one in which the abrasive friction wheel is protected so that it will not injure or soil the thumb of the user or permit the user's thumb to accidentally contact therewith if slipped from the thumb wheel 40.

The foregoing description is directed solely 40 towards the construction illustrated, but I desire it to be understood that I reserve the privilege of resorting to all the mechanical changes to which the device is susceptible, the invention being defined and limited only 45 by the terms of the appended claims.

I claim—

1. In a pocket lighter, a fuel reservoir, a wick extending therefrom, a pyrophoric tube supported on said reservoir, a friction 50 wheel adjacent the end of said tube, a guard for said wheel supported by said tube, a trunnion on which said wheel is supported extending into said guard, and a separate washer on said trunnion between said wheel 55 and reservoir to space the same therefrom, said trunnion having threaded engagement with said reservoir and removable therefrom to permit removal of said washer and removal of said wheel from beneath said 60 guard.

2. In a pocket lighter, a fuel reservoir, a wick extending therefrom, a pyrophoric tube supported on said reservoir, a friction wheel adjacent the end of said tube, a thumb 65 wheel of a larger size than said friction

wheel and operatively connected thereto at a point beneath it to rotate therewith, a band-shaped guard carried by said tube about said friction wheel, a trunnion having threaded engagement with said reservoir 70 and of a size smaller than the opening through said band guard on which said wheels are mounted, a separate washer on said trunnion between said thumb wheel and reservoir whereby when said trunnion 75 is removed, said washer is free to be removed from beneath said wheels and whereby the wheels may be dropped from said band guard and removed from said lighter.

3. In lighter construction, in combination, 80 a fuel casing, a tube for holding pyrophoric material mounted in a horizontal position on the top wall of said casing, a friction wheel adjacent the end of said tube for engaging said pyrophoric material, a guard extending 85 from said tube about said friction wheel, a thumb wheel between said guard and the casing adapted to be turned manually to rotate said friction wheel, said guard having an opening, and a removable member adapted 90 to be positioned through said opening and passing downwardly through said friction wheel and thumb wheel and into said casing to rotatably support said thumb wheel and said friction wheel.

4. In lighter construction, in combination, 95 a fuel casing, a tube for holding pyrophoric material mounted in a horizontal position on the top wall of said casing, a friction wheel adjacent the end of said tube for engaging 100 said pyrophoric material, a guard extending from said tube about said friction wheel, a thumb wheel between said guard and the casing adapted to be turned manually to rotate said friction wheel, said guard having an opening in the top above said friction wheel, and a threaded member having a head positioned in said opening and passing 105 downwardly through said friction wheel and through said thumb wheel and into said casing to rotatably support said thumb wheel and said friction wheel.

5. In lighter construction, in combination, 110 a fuel casing, a tube for holding pyrophoric material mounted upon the top wall of said casing in spaced relation thereto and with its axis substantially horizontal, one end of said tube being positioned adjacent one end of said top wall of the casing, a friction wheel adjacent said end of the tube with its axis 115 vertical and for engaging the pyrophoric material, a spring in said tube for urging the pyrophoric material against said friction wheel, a screw in the other end of the tube for adjusting the compression of said 120 spring, a thumb wheel beneath said friction wheel adapted to be turned manually to rotate said friction wheel against said pyrophoric material, a wick communicating with the interior of said casing and projecting 125 130

adjacent to said friction wheel in the path of sparks thrown by said friction wheel from said pyrophoric material, a cover for said wick mounted on the top of the casing for movement into and out of position over said wick, a guard projecting from said tube substantially covering the periphery of said friction wheel on the side thereof opposite said wick and on the side thereof opposite the tube end and broken away adjacent said wick to permit passage of the sparks, said thumb wheel being positioned beneath said guard and said guard having an opening at the top above said friction wheel, and a removable threaded member having a head positioned in said opening and passing downwardly through said friction wheel, through said thumb wheel and into said casing to rotatably and removably hold said friction wheel and said thumb wheel in position.

6. In lighter construction, in combination,

a fuel casing, a tube for holding pyrophoric material mounted in a substantially horizontal position on the top wall of said casing, a friction wheel adjacent the end of said tube for engaging said pyrophoric material, a rigid part projecting outwardly from the end of said tube adjacent said friction wheel, a thumb wheel beneath said friction wheel, said projecting part of said tube having an opening therein above said friction wheel, and a trunnion in said opening and extending through said friction wheel, through said thumb wheel and into said casing, said friction wheel and said thumb wheel being rotatable upon said trunnion and said trunnion being held against rotation.

In testimony whereof I affix my signature.

WILLIAM J. BUTLER.
